(57) **CLAIM**

The ornamental design for a conduit dredge, as shown and described.

DESCRIPTION

FIG. 1 is a front, left, and top perspective view of a conduit dredge design showing my new design.

FIG. 2 is a rear, right, and bottom perspective view thereof.

FIG. 3 is a front view thereof.

FIG. 4 is a rear view thereof.

FIG. 5 is a left side view thereof.

FIG. 6 is a right side view thereof.

FIG. 7 is an enlarged top view thereof.

FIG. 8 is an enlarged bottom view thereof.

FIG. 9 is an enlarged view of portion 9 shown in FIG. 1; and, FIG. 10 is another perspective view showing the conduit dredge when the tool is in the state of use.

The dot-dash broken lines depict the boundaries of the enlargements that form no part of the claimed design. The broken lines in the drawings depict portions of a conduit dredge that form no part of the claimed design.

1 Claim, 10 Drawing Sheets(56)
